INVENTOR.

UNITED STATES PATENT OFFICE.

ROBERT MACDONALD, OF HOPE, RHODE ISLAND.

SHOE-RACK.

No. 819,777.

Specification of Letters Patent.

Patented May 8, 1906.

Application filed August 30, 1905. Serial No. 276,484.

To all whom it may concern:

Be it known that I, ROBERT MACDONALD, a citizen of the United States, residing at Hope, in the county of Providence and State of Rhode Island, have invented certain new and useful Improvements in Shoe-Racks, of which the following is a specification.

My invention relates to improvements in shoe-racks, the purpose of the same being to provide a simple and effective way of holding shoes in an orderly manner either for purposes of display in a dealer's window or for individual or domestic use at home, one of the principal features of my invention being its adaptability to shoes of different sizes.

The above objects are accomplished by the device shown in the accompanying drawings, in which—

Figure 1 is a perspective view; Fig. 2, a section through x x of Fig. 1, showing shoes in position; and Fig. 3, a detail of the holding-clip.

In Fig. 1, a a' is a suitable frame, of wood or other material, of any convenient size and adapted to hold any desired number of clips. This frame may or may not have one or more cross-bars a^2 , according to the desired capacity of the frame.

e is a hook for suspension of the frame, and b b are wire clips secured to the frame by screws c or any other equivalent method.

d d are wires secured transversely to the frame forming supports for the sole of the shoe, as shown in Fig. 2.

The shape of the clips b b is important, it being in substance an elliptical or approximately elliptical loop open at the upper portion and terminating in ends bent at right angles or approximately right angles to the plane of the loop, these ends having suitable eyes, as shown at b' b' .

The operation of this clip in holding shoes of different sizes is shown in Fig. 3. The loop normally is of a size to fit the smallest-sized heel that will be apt to be used on the frame; 45 but the projecting upper ends of the clip between the loop and the frame spring apart on the insertion of larger heels, as shown by the dotted lines in Fig. 3, thus holding such larger sizes securely. 50

Having now described my invention, what I claim, and desire to secure by Letters Patent, is—

1. A shoe-rack consisting of a rectangular frame having a central cross-bar, an eye attached to one end of said frame for suspending the frame from a suitable support, a plurality of clips consisting of bent loops having eyes at their extremities, screws passing through the eyes of the loops of the clips and 6c securing the same to the upper cross-bar and the central cross-bar of the frame, said loops being adapted to be sprung apart at the opening thereof so as to accommodate the shoe-heels and supports carried by the vertical side bars of said frame and projecting forwardly from the frame to support the soles of shoes suspended in said loops. 65

2. A shoe-rack comprising a frame, a plurality of clips attached to the frame, each 70 consisting of a bent wire having its ends at right angles to its central portion and a support of substantially U shape carried by the frame below said clips.

In testimony whereof I affix my signature 75 in presence of two witnesses.

ROBERT MACDONALD.
